ROTARY PUMP

James P. Johnson, Shaker Heights, Ohio

Application October 26, 1948, Serial No. 56,489

3 Claims. (Cl. 103—121)

1

The present improvements relating generally as indicated to rotary pumps are more particularly concerned with rotary pumps having improved performance characteristics including high mechanical and volumetric efficiency and capable of high speed and high pressure operation.

In the most familiar types of rotary pumps, viz. the gear pump and the sliding vane pump, the former has the disadvantage of trapping fluid on the discharge side at the point of gear intermesh resulting in noisy operation and low mechanical efficiency particularly at high rotative speeds, and the latter has the disadvantage of excessive leakage at the sides and tips of the vanes particularly at high speeds, the tips of the vanes being in line contact or at the most in relatively narrow surface contact with the stator or rotor whereby to offer low resistance to leakage. Furthermore, such sliding vanes are subjected to considerable wear and generate excessive frictional heat in view of the high unit pressure contact of the tips thereof with the stator or rotor and the relatively great distance traversed by the tips while in such high unit pressure contact, vis. the perimeter of the surface engaged thereby multiplied by the revolutions per minute of the stator and rotor relative to one another.

Accordingly, it is one of the primary objects of this invention to provide a rotary pump of a form avoiding the aforesaid difficulties and capable of high pressure-high speed operation at high mechanical and volumetric efficiency.

Another object of this invention is to provide a rotary pump in which a vane or like element thereof reciprocably slides slowly relative to pump members coupled thereby in accordance with the eccentricity of said pump members and serves as a driving member between said eccentrically disposed pump members and forms with said members a variable volume cavity. In this way, a passage in one of said pump members establishes selective communication between such cavity and ports leading into the pump casing in which said pump members are rotatably supported.

Another object of this invention is to provide a rotary pump which essentially comprises an outer pump member having a running fit within the pump casing and an eccentrically disposed inner pump member within said outer pump member and rotatably supported by the pump casing, said members being connected in driving relation by a driving member having non-rotatable but transversely slidable connections with said members, such sliding occurring along rela-

2

tively large surface areas whereby to minimize leakage or bypass therewith.

Another object of this invention is to provide a rotary pump of the character indicated in which the relatively small amount of such sliding consequently reduces wear and heat generation between the driving and pump members to a minimum. Furthermore, because of the large area contact between such driving and pump members, the unit pressure therebetween is relatively low, further reducing wear and heat generation.

Another object of this invention is to provide a rotary pump in which the aforesaid driving member is reciprocably mounted in and on the inner and outer pump members respectively for varying the capacity of the cavities defined thereby with said pump members.

Another object of this invention is to provide a rotary pump including a universal coupling between the eccentrically disposed pump members thereof for permitting rotation of each pump member about its own axis.

Another object of this invention is to provide a rotary pump as aforesaid including novel means for varying the displacement thereof.

Another object of this invention is to provide a reversible rotary pump which may be operated in opposite directions without necessitating changing of any of the parts thereof.

To the accomplishment of the foregoing and related ends, said invention, then, comprises the features hereinafter fully described and particularly pointed out in the claims, the following description and the annexed drawings setting forth in detail certain illustrative embodiments of the invention, these being indicative, however, of but a few of the various ways in which the principle of the invention may be employed.

In said annexed drawings—

40 Fig. 1 is a cross section view of one embodiment of the invention taken substantially along the line 1—1, Fig. 2;

Fig. 2 is a cross section view taken substantially along the line 2—2, Fig. 1;

45 Fig. 3 is a perspective view of the driving members used in the pump of Figs. 1 and 2;

Fig. 4 schematically illustrates the operation of the pump of Figs. 1 and 2;

Fig. 5 is a cross section view similar to Fig. 1 (pump casing and liner omitted) of a modification omitting one of the two driving members illustrated in Fig. 1;

50 Fig. 6 is a cross section view similar to Fig. 1 (pump casing and liner omitted) of a further modification illustrating the driving members

reversed from the position thereof illustrated in Fig. 1;

Fig. 7 is a cross section view diametrically through another embodiment of this invention;

Fig. 8 is a perspective view of the driving members employed in Fig. 7;

Fig. 9 schematically illustrates the operation of the pump of Fig. 7;

Fig. 10 is a cross section view similar to Fig. 7 except with one driving member and with the pump casing and liner omitted;

Fig. 11 is a diametrical cross section view illustrating a pump casing and adjustable liner therein adapted to be used with any of the pumps illustrated for varying the capacity thereof; and

Fig. 12 is a cross section view similar to Fig. 11 illustrating a liner which is automatically adjusted in response to the pressure of the fluid delivered by the pump.

Referring now more particularly to the drawings and first to the pumps illustrated in Figs. 1 through 6, there is shown therein a pump casing part 1 formed with a bore 2 therethrough and ports 3 and 4 leading into such bore. At the opposite ends of said casing part 1 are cover plates 5 and 6 closing the ends of the bore 2 and thereby defining a cylindrical chamber, said plates being provided with bushings 7 and 8 or like bearings for rotatively supporting a rotor or inner pump member 9 therein with the axis 10 thereof eccentric relative to the axis 11 of such chamber formed in said casing. The aforesaid chamber may be lined if desired with a sleeve or liner 12 and end plates 13 and 14 fabricated from a suitable bearing material. Said sleeve 12 is fixed in casing part 1 and is slotted as shown to provide openings 15 and 16 respectively registering with the ports 3 and 4. Said casing part 1 and cover plates 5 and 6 are held together to form a unitary pump casing as by the bolts and nuts 17.

Within said sleeve 12 and surrounding said inner pump member 9 is a cylindrical outer pump member 18 having a close running fit with the pump chamber side and end walls as defined by the inner surface of said sleeve 12 and the inner faces of said end plates 13 and 14. Said outer pump member 18 is rotatable about an axis coinciding with the axis 11 of the casing bore 2 and eccentric relative to the axis 10 of said inner pump member 9. Said outer pump member 18 is formed with circumferentially spaced passages 19 therethrough each adapted to successively communicate with ports 3 and 4 through openings 15 and 16 in sleeve 12 during rotation of said outer pump member, such passage leading into the corners of the generally rectangular bore 20 in said outer pump member.

The inner pump member 9 is formed with a pair of radially extending slots 21 and 22 intersecting at right angles in which are fitted for radial sliding a pair of driving members 23 and 24 each driving member preferably being made in two T-shaped parts abutting one another at their inner ends and having its outer ends formed with laterally extending flanges 25 making sliding contact with the opposed parallel flat surfaces of the bore 20 in the outer pump member 18. Said driving members 23 and 24 are shaped as best shown in Fig. 3 with notches 26 and 27 to permit independent sliding thereof in the slots 21 and 22 along paths at right angles to one another. Obviously, said driving members may each be of one-piece construction if desired where the slots 21 and 22 are such that said driving members are assembled by endwise or axial move-

ment along the slots from one end of the inner pump member 9. The sides of said driving members 23 and 24 have a close sliding fit with such slots and the outer ends thereof have a close sliding fit with the flat surfaces in the bore 20 and likewise the opposite end faces of the vanes have a close sliding fit with the inner surfaces of the end plates 13 and 14. It is thus apparent that said driving members divide the space within said outer member 18 into four independent cavities each having a passage 19 leading thereto. It is to be noted that the lateral flanges 25 of said driving members provide a wide bearing for precluding cocking and binding between the driving and outer pump members caused by the driving of one through the other in a manner as will hereinafter appear, and further provide large area sealing surfaces to reduce bypass between such cavities to a minimum.

In the present case the inner pump member 9 is power driven through the splined shaft 28 projecting through cover plate 6 but obviously the outer pump member 18 may be power driven, if desired.

As best shown in Fig. 4, the operation of the above-described pump is as follows. Considering one cavity A formed between the driving members 23 and 24, and pump members 9 and 18 rotated clockwise it can be seen from Fig. 4, positions I-V, that the volume of such cavity A increases from a minimum to a maximum and therefore the associated passage 19 leading thereto will be in communication with the intake opening 15 and port 3 in sleeve 12 and casing part 1 respectively. From position V through position VIII and thence to position I the volume of such cavity A progressively decreases from a maximum to a minimum and therefore the associated passage 19 is brought into communication with the discharge opening 16 and port 4 in sleeve 12 and casing part 1 respectively.

The other three cavities defined between the driving members and the pump members similarly increase and decrease during one revolution of the pump members, such change in volume being attributed to the eccentric relation of the pump members and permitted by the transverse slide mounting of the driven members along paths as shown. In this way, one revolution of the driving and pump members effects intake and discharge of fluid into and from four independent cavities. Obviously, the pump assembly may be rotated counterclockwise, in which case the ports 3 and 4 are discharge and intake ports respectively.

In the modification illustrated in Fig. 5, the single driving member 29, preferably of one-piece construction, forms two cavities B and C with the inner and outer pump members 30 and 31 whereby rotation of said pump members effects increase and decrease of the volumes of such cavities B and C in a manner similar to that described in connection with the pump of Figs. 1 through 4. As in the structure of Figs. 1 through 4, the pump of Fig. 5 is so arranged that the cavities B and C are alternately in communication with the intake and discharge ports in a pump casing (not shown) as afforded by the passages 32 and 33 through the wall of outer pump member 31 into cavities B and C.

In Fig. 6 there is illustrated a still further modification of the pump of Figs. 1 through 4 wherein the driving members 34 and 35 are radially slidably in radially extending perpendicular slots formed in the outer pump member 36,

said driving members being formed with laterally extending flanges 37 having reciprocable sliding engagement with opposed parallel flat faces on the inner pump member 38. In this case the diametrically opposed portions of each driving member are connected by a web 39 and 40 extending through slots therefor formed in said inner pump member, such slots being of size such as to accommodate transverse sliding of the respective driving members without exposing such slots to the pump cavities defined between said driving and pump members. Passages 41 lead from the exterior of outer pump member 36 to the independent cavities defined therein.

Inasmuch as the operation of the Fig. 6 pump is essentially the same as that illustrated in Figs. 1 and 4, the same need not now be repeated.

It is now apparent that during one revolution of the driving and pump members in the pumps of Figs. 1 through 6, the ends of the driving members provided with the lateral flanges slide back and forth once along the flat surfaces engaged thereby and the other ends slide radially in and out once in the pump member which carries the same, such sliding movements occurring between surfaces of relatively large area and being but a small fractional portion of the amount of sliding of the vane tips in conventional sliding-vane type pumps whereby to minimize leakage and friction. Furthermore, the outer pump member is, in each case, in the nature of a cylindrical plug as used in cylindrical valves having large bearing surfaces and formed with passages alternately connecting cavities defined in the outer pump member with intake and discharge ports leading into the pump casing.

The embodiment of the invention illustrated in Figs. 7, 8 and 9 comprises a pump casing 1 including ports 3 and 4 and a sleeve 12 with openings 15 and 16 precisely the same as the pump of Figs. 1 and 2. As in Figs. 1 and 2 the pump of Fig. 7 will be preferably provided with cover plates 5 and 6 and with end plates 13 and 14 adapted to have a sliding fit with the end faces of the driving and pump members to be presently described.

As shown in Fig. 7, the outer pump member 42 of tubular form is formed with a notch 43 on its inner face with which one end of a driving member 44 extending through a radial slot 45 in the eccentrically disposed inner pump member 46 has a driving and pivotal connection. The diametrically opposed wall of said outer pump member 42 is formed with a notch or recess 47, the bottom wall of which is cylindrical, of radius R struck from a center preferably located at the bottom wall of notch 43. Said driving member 44 also has a cylindrical end face of the same radius R making surface contact with such recess 47.

Diametrically through said inner pump member 46 and at right angles to the aforesaid slot 45 therein is another slot 48 slidably receiving another vane-like member 49 which has its opposite ends in slidable engagement with parallel diametrically opposed flat faces 50 formed in the outer pump member 42. The last-named member 49 is provided with cylindrical end faces preferably of radius S struck from the center of said member. Said members 44 and 49 are formed with notches 51 and 52 as shown in Fig. 8 to permit movement thereof in their respective slots 45 and 48 along paths intersecting at right angles. In this case, the inner pump member 46 may be provided either with at least one slot extending

through one end thereof whereby one of the members 44 and 49 can be positioned in the other slot and the other of said members then moved axially along its through slot into nested position with respect to said one of the members or with at least one slot sufficiently long to permit axial displacement of the member therein to a position permitting radial insertion of the other member in the other slot.

As shown in Fig. 7, said members 44 and 49 define four separate cavities with the pump members 42 and 46, the former being formed with passages 53 each communicating with one of such cavities and adapted upon rotation of said member 42 to bring such cavities successively in communication with intake passage 15 and port 3 and discharge passage 16 and port 4 in said sleeve 12 and casing 1 respectively.

Referring now to Fig. 9, the rotation of inner pump member 46 clockwise from position I to position V and corresponding driving of outer pump member 42 through the non-rotatable connection of driving member 44 with said members effects a progressive increase in the volume of cavity D and likewise rotation of pump members 42 and 46 from position V through position VIII and back to position I effects a progressive decrease in the volume of such cavity D. Thus, the passage 53 leading to cavity D is successively brought into communication with the intake and discharge ports of the pump. The other three cavities of this form of pump will similarly increase and decrease in volume during one revolution of the pump members 42 and 46. Here again, as in the previously described forms of pumps, the inner pump member 46 may be rotated counterclockwise in which case the port 4 becomes an intake and the port 3 a discharge.

As evident from a study of Fig. 9, the rotation of the pump members 42 and 46 effects a slow rocking or oscillation of driving member 44 (about the notch 43 as a pivot) in cylindrical notch 47 and a slow tilting and transverse sliding of member 49 along the faces 50 of the outer pump member 42, said members 44 and 49 and the surfaces slidably and drivingly engaged thereby being so formed that in any position of the pump members an efficient seal is effected to minimize bypass or leakage of fluid therewith.

The modification illustrated in Fig. 10 is essentially the same as that of Fig. 7 except that the member 49 has been omitted, the remaining driving member 44 serving to divide the chamber defined between outer pump member 54 and the inner pump member 55 into two separate cavities E and F, which cavities through the passages 56 are successively brought into communication with the intake and discharge ports of the pump. The operation of the Fig. 10 pump is substantially the same as illustrated in Fig. 9 and therefore repetition thereof has not been deemed necessary.

It is now apparent that, in the pump structures of Figs. 7 through 10, driving members and other cavity forming members thereof simply slide back and forth slowly for relatively short distances both transversely and radially whereby to overcome the objection of high vane tip speeds and excessive wear thereof as encountered with conventional sliding-vane type pumps.

In Fig. 11 there is shown the basic elements of a variable volume pump comprising a pump casing 57 having an oblong bore 58 into which leads the ports 59 and 60 and within which casing bore a liner or sleeve 61 is fitted, said liner being provided with axially extending ribs 62 and 63 fitting

into similarly disposed grooves 64 and 65 in said casing. Threaded into one of said ribs of said liner is a screw 66 rotatable but axially fixed in said casing as by a pin 67 engaged in a groove in the screw and locked as by a lock nut 68. As apparent, loosening of lock nut 68 and rotation of said screw 66 effects shifting of liner 61 in casing bore 58 so that the axis of said liner may be offset or eccentric any desired amount relative to the axis of the inner pump member (not shown) adapted to be disposed therein. Said liner 61 is of the same general construction as liner 12 illustrated in Figs. 1 and 7 provided with slots 69 and 70 respectively registering with ports 59 and 60 and therefore any of the pump and driving member assemblies illustrated may be disposed therein. If desired, the grooves 64 and 65 may be provided with vents 71 and 72 to prevent trapping of fluid therein between the ends of the ribs and the bottoms of the grooves, such vents leading to the intake side of the pump casing.

It can now be seen that the capacity of a pump may be readily varied between zero (no eccentricity between the pump members) and maximum (maximum eccentricity between the pump members) simply by adjusting the screw 66.

In Fig. 12 is illustrated a variation of the pump of Fig. 11 in which the sleeve 73, in response to the pressure of the fluid delivered by the pump and acting on the pump and driving members within said sleeve, is shifted transversely of the casing 74 to vary the eccentricity between the pump members. One manner of accomplishing such action is to provide diametrically opposed extensions 75 and 76 on the sleeve fitting into recesses 77 and 78 formed in the pump casing, one such extension 76 being adapted to engage an adjustable abutment screw 79 threaded in said casing and extending into recess 78, said screw determining the maximum eccentricity and thus maximum delivery of the pump, and being locked in an adjusted position as by the lock nut 80.

The other extension 75 has a recess in which is disposed a spring 81 compressed between said sleeve 73 and an adjusting screw 82 also threaded in casing 74 and extending into recess 77 for engagement by the sleeve 73 to determine the minimum eccentricity and thus the minimum delivery of the pump, said screw being locked in adjusted position as by the lock nut 83.

The casing 74 is provided with ports 84 and 85 and said sleeve 73 is provided with slots 86 and 87 respectively communicating with such ports and as indicated with reference to Fig. 11, said sleeve 73 may contain therein any of the pump and driving member assemblies herein disclosed. In Fig. 12 the sleeve 73 is shown in the position it assumes when delivering the maximum for which it is adjusted by screw 79. Under varied conditions of operation, said sleeve will shift back and forth transversely of its axis and at times the shoulder 88 thereof will engage the end of screw 82 to provide a minimum delivery which may be zero if desired (axis of sleeve coinciding with axis of inner pump member) or any value between zero and maximum, the maximum being determined by the adjustment of screw 79.

Having thus described several embodiments of this invention it is now understandable that there is provided herein eccentrically disposed pump members one within the other which are non-rotatably connected together thus eliminating the high velocity tip speeds inherent in sliding-vane type pumps. Also, the provision of relatively wide surface contact and slow relative movement

between the driving and pump members minimizes leakage therewith. The pumps herein disclosed also avoid the difficulties of gear pumps as previously stated. A still further feature of the present invention resulting from the relatively wide surface contact and relatively small distance of sliding between the driving and pump members reduces the wear and heating of such sliding surfaces to a minimum. Likewise, the wide bearing surfaces establish a driving angle considerably greater than one which would induce cocking and binding.

Briefly summarized, the present invention in rotary pumps comprises providing a casing in which pump members one within the other are rotatable about eccentrically disposed axes and in which a driving member between said pump members serves to non-rotatably connect said pump members together so that rotation of any of said members effects rotation of all of them and consequent pumping action as permitted by the angularly disposed transverse sliding connections between said driving and pump members. As apparent, this basic thought runs through all of the forms of the invention illustrated, such various forms, of course, to be regarded as merely typical and further modifiable without departing from the spirit of the invention.

Although the present improvements have been specifically described in relation to pumps in which fluid is drawn in through an intake port and discharged under pressure from a discharge port, it will be understood by those skilled in the art that the present improvements can be readily used as a motor wherein fluid under pressure entering the casing through one port effects rotation of the assembly therein, the fluid discharged from the other port being exhausted or directed to a reservoir.

Other modes of applying the principle of the invention may be employed, change being made as regards the details described, provided the features stated in any of the following claims, or the equivalent of such, be employed.

I therefore particularly point out and distinctly claim as my invention:

1. A rotary pump comprising a hollow casing provided with intake and discharge ports leading thereto, an outer pump member rotatable within said casing about its central axis and provided with a passage successively communicating with such ports during rotation of said outer pump member, said outer pump member being formed with a bore including two pairs of diametrically opposed wall portions of which one pair are parallel flat surfaces and the other pair has one portion of cylindrical form of radius struck from the other portion of such other pair of opposed portions, an inner pump member rotatable within said outer pump member about an axis disposed eccentric to the axis of said outer pump member and formed with a pair of radially extending slots therethrough, and a pair of vane-like members respectively radially slidable in such slots, one of said vane-like members having its opposite ends in driving pivotal engagement with the other portion of such other pair of wall portions and transverse slidable engagement with the wall portion of cylindrical form, and the other of said vane-like members having its opposite ends in transverse slidable engagement with such one pair of wall portions, said vane-like members forming a cavity with said pump members having communication with such passage, the ends of said other of said vane-like members

being of cylindrical form of diameter substantially equal to the distance between such one pair of wall portions.

2. A rotary pump comprising a hollow casing provided with intake and discharge ports leading thereto, an outer pump member rotatable within said casing about its central axis and provided with a passage successively communicating with such ports during rotation of said outer pump member, said outer pump member being formed with a bore including two pairs of diametrically opposed wall portions of which one pair are parallel flat surfaces and the other pair has one portion of cylindrical form of radius struck from the other portion of such other pair of opposed portions, an inner pump member rotatable within said outer pump member about an axis disposed eccentric to the axis of said outer pump member and formed with a pair of radially extending slots therethrough, and a pair of vane-like members respectively radially slidable in such slots, one of said vane-like members having its opposite ends in driving pivotal engagement with the other portion of such other pair of wall portions and transverse slidable engagement with the wall portion of cylindrical form, and the other of said vane-like members having its opposite ends in transverse slidable engagement with such one pair of wall portions, said vane-like members forming a cavity with said pump members having communication with such passage, the ends of said other of said vane-like members being of cy-

lindrical form of diameter substantially equal to the distance between such one pair of wall portions, and the end of said one of said vane-like members which is transversely slidable on the wall portion of cylindrical form likewise being of cylindrical form coaxial with the aforesaid wall portion of cylindrical form.

3. The structure according to claim 2 further characterized in that the wall portion with which one end of said one of said vane-like members has a driving, pivotal connection is in the form of a notch for receiving such one end of the aforesaid vane-like member.

JAMES P. JOHNSON.
